US00D477696S

(12) **United States Design Patent** (10) Patent No.: **US D477,696 S**
(45) Date of Patent: ** Jul. 22, 2003

(54) **NAP CLEANER**

(76) Inventor: **Abdal-Rahim Jabbar**, 2550
Pennsylvania, Beaumont, TX (US)
77701

(**) Term: **14 Years**

(21) Appl. No.: **29/159,858**

(22) Filed: **Apr. 30, 2002**

(51) LOC (7) Cl. **15-05**

(52) U.S. Cl. **D32/1**

(58) Field of Search D32/1, 6; 134/138
